(57) **CLAIM**

We claim, the ornamental design for a display screen or portion thereof with animated graphical user interface, as shown and described.

DESCRIPTION

FIG. 1 is a first image in a sequence for a display screen or portion thereof with animated graphical user interface showing our new design;

FIG. 2 is a second image in a sequence thereof;

FIG. 3 is a third image in a sequence thereof;

FIG. 4 is a fourth image in a sequence thereof;

FIG. 5 is a fifth image in a sequence thereof;

FIG. 6 is a sixth image in a sequence thereof;

FIG. 7 is a seventh image in a sequence thereof;

FIG. 8 is an eighth image in a sequence thereof;

FIG. 9 is a ninth image in a sequence thereof;

FIG. 10 is a tenth image in a sequence thereof;

FIG. 11 is an eleventh image in a sequence thereof;

FIG. 12 is a twelfth image in a sequence thereof; and,

FIG. 13 is a thirteenth image in a sequence thereof.

The broken lines are for environmental purposes only and form no part of the claimed design.

The appearance of the design transitions sequentially between the images shown in FIGS. 1-13. The process or period in which one image transitions to another forms no part of the claimed design.
